CLAIM

The ornamental design for a combination handset front cover and set of keys, as shown and described.

DESCRIPTION

FIG. 1 is a perspective front view of a combination handset front cover and set of keys showing our new design;

FIG. 2 is a front view thereof;

FIG. 3 is a rear view thereof;

FIG. 4 is a right side view thereof;

FIG. 5 is a left side thereof;

FIG. 6 is a top view thereof; and,

FIG. 7 is a bottom view thereof.

The broken lines immediately adjacent the claimed surfaces represent boundaries of the claimed design. All other broken lines are directed to environment. The broken lines and unshaded regions bounded by broken lines form no part of the claimed design.
